UNITED STATES PATENT OFFICE.

ALBERT H. STEELE, OF WORCESTER, MASSACHUSETTS.

LOOM-SHUTTLE.

SPECIFICATION forming part of Letters Patent No. 447,500, dated March 3, 1891.

Application filed July 9, 1890. Serial No. 358,169. (No model.)

To all whom it may concern:

Be it known that I, ALBERT H. STEELE, of the city and county of Worcester, and State of Massachusetts, have invented certain new and useful Improvements in Loom-Shuttles; and I do hereby declare that the following is a full, clear, and exact description thereof, reference being had to the accompanying drawings, forming a part of this specification, and 10 in which—

Figure 1 represents a plan of a shuttle with my improvement applied thereto. Fig. 2 is a vertical section through said shuttle taken on line *a*, Fig. 1. Fig. 3 represents a modification 15 of one of the spindle-bearings. Fig. 4 is a cross-section through the spindle and a front view of my improved spindle-bearing for detachably holding the end of the spindle, as will be hereinafter more fully specified; and 20 Figs. 5, 6, and 7 are a front view, back view, and top end view, respectively, of said spindle-bearing.

My invention relates to shuttles employed on narrow-fabric looms, and more particularly 25 to the spindle fastenings or bearings of said shuttles.

It consists in making the bearing of the detachable end of the spindle with a lateral or side spring adapted to securely hold, and at 30 the same time permit of the easy removal of said detachable end, as will be hereinafter more fully set forth.

To enable others skilled in the art to which my invention appertains to better understand 35 the nature and purpose thereof, I will now proceed to describe it more in detail.

In the drawings, *A* indicates the shuttle-body; *B*, the spindle, on which is fitted the usual spool or bobbin, (not shown in this instance;) *C*, the spring friction-pad; and *D*, my improved spindle fastening or bearing previously referred to. Said bearing is fitted in a recess in the shuttle-frame *A'*, as usual, flush with the surface thereof, and consists 45 of the back plate *c*, preferably having the spur *c'* projecting from its rear side to hold said bearing when fitted in position. To the face of said back plate *c* is secured a bow-shaped plate *d*, one half *d'* being secured to plate *c*, 50 and forming a rigid side to the slot *e*, and the other or free end *d''* thereof acting as a spring

to hold the end *f* of spindle *B* from slipping out when forced down into slot *e* between said rigid and spring sides *d'* *d''*, as is shown in Fig. 4 of the drawings. In practice the upper or outer end of the slot is made a little narrower than at the bottom thereof, so that when the end of the spindle is forced down into the same it will be securely held therein; and to facilitate the insertion of the end of the 60 spindle, as well as to form a longer bearing-surface in the slot, said end is preferably bent or curved into the form of an upturned hook *g*, as is shown in Fig. 2.

The construction of the spindle, as well as 65 the manner of holding the pointed end *g'* thereof in the shuttle, I do not claim as new.

It is preferable to fit said end against a metal bearing-piece *h* fitted in the shuttle-frame; but if desired said bearing may be 70 dispensed with, and the end of the spindle fitted in a suitable indentation or recess formed in said frame to receive it, as is shown in Fig. 3.

It is obvious that a spindle fastening or bearing made as aforesaid is very simple in 75 construction, while at the same time durable and effective in use.

The spindle is not only held sufficiently secure to prevent its slipping out accidentally, but may also be easily removed by hand in 80 the usual way as required in practice.

What I claim as new, and desire to secure by Letters Patent, is—

1. In a loom-shuttle, the spindle fastening or bearing *D*, having the vertical slot *e* to receive the end of the spindle, and the spring *d'* at the side thereof, substantially as and for 85 the purpose set forth.

2. In a loom-shuttle, the combination of shuttle-frame *A'* and spindle *B* with spindle 90 fastening or bearing *D*, having the vertical slot *e* and the spring *d''* at the side thereof, substantially as and for the purpose set forth.

3. In a loom-shuttle, the combination of shuttle-frame *A'*, spindle *B*, and bearing *h* 95 with bearing *D*, having the vertical slot *e* and the spring *d''* at the side thereof, substantially as and for the purpose set forth.

ALBERT H. STEELE.
